UNITED STATES PATENT OFFICE.

JOHN NICHOLAS SCHUMACHER, OF CHICAGO, ILLINOIS.

BABBITTING DEVICE.

SPECIFICATION forming part of Letters Patent No. 715,161, dated December 2, 1902.

Application filed April 25, 1902. Serial No. 104,645. (No model.)

To all whom it may concern:

Be it known that I, JOHN NICHOLAS SCHUMACHER, a citizen of the United States, and a resident of Chicago, in the county of Cook and State of Illinois, have invented a new and Improved Babbittting Device, of which the following is a full, clear, and exact description.

The object of the invention is to provide a new and improved babbittting device designed for babbittting the hubs of loose pulleys, idlers, and like articles and arranged to keep the pulley or other article in proper central position relative to the core or shaft to insure the proper formation of the babbitt bearing and requiring no subsequent boring or turning of the bearing.

The invention consists of novel features and parts and combinations of the same, as will be more fully described hereinafter and then pointed out in the claims.

A practical embodiment of the invention is represented in the accompanying drawings, forming a part of this specification, in which similar characters of reference indicate corresponding parts in all the views.

Figure 1 is a sectional side elevation of the improvement as applied. Fig. 2 is a sectional side elevation of the pulley after it is babbitted. Fig. 3 is a sectional plan view of the upper collar in position on the shaft or core, and Fig. 4 is a perspective view of the upper collar.

Through the hub A' of the pulley, idler, or like device A extends the shaft or core B, preferably held in an upright position during the babbittting process, but which may be placed in a horizontal position, and on the said shaft or core are removably secured the collars C and D, held in position on the core or shaft by set-screws E, as plainly indicated in Figs. 1 and 3. The collars C and D are provided with annular concentric ridges C' D', adapted to engage corresponding seats or recesses A² A³, formed concentrically in the ends of the hub A', so as to hold the hub and pulley A in exact concentric position relative to the shaft or core B.

The lower collar C is the supporting-collar for the pulley, and the upper collar D is the pouring and vent collar and is provided with the pouring-channel D², leading to the upper reduced end of the bearing-recess A⁴, formed in the hub for receiving the Babbitt metal

forming the bearing F, as plainly shown in Fig. 2. The lower reduced end of the bearing-recess A⁴ is closed by the supporting-collar C during the babbittting process. In the collar D is also formed a vent-opening or channel D³, preferably located diametrically opposite the channel D² and likewise in register with the recess A⁴.

Now when the several parts are in the position shown in Fig. 1 and the Babbitt metal is poured into the channel D² then it flows into the recess A⁴ and fills the same around the shaft or core B, as the collar C prevents escape of the metal from the recess. Air can escape from the recess A⁴ through the air-vent D³, so that the Babbitt metal forms a homogeneous bearing, thereby avoiding undesirable blow-holes. Now by having the ridges C' and D' engaging seats on the ends of the hub A' the latter is held in perfect true position relative to the shaft or core B, so that the babbitt material poured into the recess A⁴ forms a bearing for the pulley A.

Having thus described my invention, I claim as new and desire to secure by Letters Patent—

1. A babbittting device for pulleys, idlers and like articles, comprising a shaft or core on which the article to be babbitted is placed, a supporting-collar and a pouring-collar on said shaft for engaging the ends of the part to be babbitted, the said collars and the part to be babbitted being provided at their engaging ends, one with an annular concentric ridge having a flattened apex and tapering sides, and the other with a correspondingly-shaped annular seat, as set forth.

2. A babbittting device for pulleys, idlers and like articles, comprising a supporting-collar for the article, a set-screw adapted to secure said collar to a shaft or core on which the article is placed, the collar being provided at one end with an annular concentric ridge between the inner and outer walls thereof, the said ridge having a flattened apex and tapering sides and adapted to engage a correspondingly-shaped groove on the end of the article, a collar on the shaft or core adapted to engage the other end of the article, and having a longitudinal pouring-channel leading to the bearing-recess in the article, and an oppositely-located vent-channel also reg-

istering with the bearing-recess, the latter collar being also provided with an annular concentric ridge at its end similar in shape to the ridge on the first-mentioned collar and adapted to engage a groove in the corresponding end of the article to be babbitted, as set forth.

In testimony whereof I have signed my

name to this specification in the presence of two subscribing witnesses.

JOHN NICHOLAS SCHUMACHER.
